UNITED STATES PATENT OFFICE.

MARSHALL CLARKE, OF NEW YORK, N. Y.

DESIGN FOR A FLOWER-POT HOLDER.

SPECIFICATION forming part of Design No. 26,067, dated September 22, 1896.

Application filed August 6, 1896. Serial No. 601,928. Term of patent 14 years.

To all whom it may concern:

Be it known that I, MARSHALL CLARKE, a citizen of the United States, residing at New York, in the county and State of New York, have invented and produced a new and original Design for Flower-Pot Holders or Lifters, of which the following is a specification.

This design relates to lifters for flower-pots; and the leading features of the design consist in a handle part, having variously-extended curves and joining-shanks connected by curved portions to return-shanks, which return-shanks are connected by curved portions to a third pair of shanks having hooked ends.

The design is illustrated by the accompanying drawings, in which—

Figure 1 is a front elevation of the holder. Fig. 2 is a side elevation of Fig. 1. The handle portion comprises the curve 2, from which extend the oppositely-curved

portions 2 3 4, joining or running into shanks 4 5, which, by curved portions 5 6, join to the return-shanks 6 7. The curved portions 7 8 join the return-shanks 6 7 to a third pair of shanks 8 9, having the hooks or hooked ends 9 10. The hooks 9 10 are extended upwardly and terminate in the plane or approximately in the plane of the inner sides of faces of the shanks 4 5 and 6 7.

What I claim as new, and desire to secure by Letters Patent, is—

The design for a flower-pot lifter substantially as shown and described.

In testimony whereof I have hereunto set my hand in the presence of two subscribing witnesses.

MARSHALL CLARKE.
